ULTRASONIC RODENT ELIMINATOR

John T. Banich, Sedalia, Mo., assignor to
Design Devices, Inc.

Filed Apr. 22, 1974, Ser. No. 463,052

Term of patent 7 years

Int. Cl. D22—06

U.S. Cl. D22—18

Fig. 1.

Fig. 2.

Fig. 3.

Fig. 4.

Fig. 5.

Fig. 6.

FIG. 1 is a perspective view illustrating an ultrasonic rodent eliminator;

FIG. 2 is a side elevational view thereof;

FIG. 3 is a front elevational view of the ultrasonic rodent eliminator;

FIG. 4 is a top plan view of the device shown in FIGS. 1-3.

FIG. 5 is a rear elevational view of the ultrasonic rodent eliminator; and

FIG. 6 is a bottom plan view of the device shown in FIGS. 1-5.

I claim:

The ornamental design for an ultrasonic rodent eliminator, as shown.
